UNITED STATES PATENT OFFICE.

CARMINE MUSTARI AND FRANCESCO BRAGNO, OF CHICAGO, ILLINOIS.

DESIGN FOR A BOX OR SIMILAR ARTICLE.

Application filed December 1, 1924. Serial No. 11,553. Term of patent 3½ years.

To all whom it may concern:

Be it known that we, CARMINE MUSTARI and FRANCESCO BRAGNO, citizens of the United States, residing in Chicago, county of Cook, and State of Illinois, have invented a new, original, and ornamental Design for Boxes or Similar Articles, of which the following is a specification, reference being had to the accompanying drawing, forming part thereof, in which the single figure is a front elevational view of a container illustrating the application of our new design.

We claim:

The ornamental design for a box or similar article, as shown.

CARMINE MUSTARI.
FRANCESCO BRAGNO.
